UNITED STATES PATENT OFFICE.

ANTOINE FRANCE, OF LIEGE, BELGIUM.

APPARATUS FOR SORTING PULVERULENT MATERIALS.

Application filed September 1, 1921. Serial No. 497,723.

To all whom it may concern:

Be it known that I, ANTOINE FRANCE, a subject of the King of the Belgians, residing at Liege, Belgium, 14 Place St. Paul, have invented certain Improvements in Apparatus for Sorting Pulverulent Materials (for which I have an application in Belgium, Oct. 14, 1913, No. 261,263), of which the following is a specification.

10 In numerous industries, it is necessary or useful to remove the dust from more or less pulverulent materials or products, in order to allow or make easier their sorting, treatment, or transformation.

15 Thus, the presence of dust in coal, the treatment of which will here be adopted as an instance for the description of the present process, is particularly troublesome in the mechanical preparation and mostly in 20 the washing of the said coal.

It is frequent that fine coal contains from 15 to 20% of non-washable dust which makes the water dirty, renders the sorting of the larger-sized particles troublesome, and requires the installation of large settling tanks wherein they settle and form coal-mud (schlamms) of very small market value. The separation of such dust in the dry state is therefore almost generally required when 30 it is desired to obtain a maximum efficiency of the washing operation, by mixing the washed products with the whole or a part of the sorted pulverulent materials in the raw state.

35 Heretofore, this separation or sorting was carried out in the dry state or in the wet state, in cumbersome apparatus of small output and low efficiency.

The apparatus forming the subject-matter 40 of the present invention makes it possible to avoid these drawbacks. It possesses the advantage of being adjustable and is sufficiently adaptable to allow its use under the most varied conditions of installation and working.

An embodiment of the present invention is, by way of example only, illustrated by the accompanying drawings in which:

45 Figs. 1 and 2 are a longitudinal and a transverse vertical section respectively through a single element apparatus.

Figs. 3 and 4 are a longitudinal and a transverse vertical section respectively through a multiple element apparatus.

50 Fig. 5 is a vertical section through several elements arranged in juxtaposition.

Figs. 6 and 7 are two different vertical sections through an element provided with a conduit of determined shape and of which the lower opening can be adjusted by means of devices forming an extension of the inner wall of the said conduit. These devices preferably consist of interchangeable conical nozzles of which the largest base is of the same inner diameter as that of the lower opening of the conduit referred to while their narrowest base is of decreasing diameter, thus affording a variable reduction of the effective size of the said opening.

The single element comprises (Figs. 1 and 2) a hopper A for the storage of the material to be treated having at the base a suitable rotary valve B regulating the feeding of the material to the chamber C. This dust-extraction chamber C in which circulates in an upward direction a current of air or gas under pressure, is of such a shape that the velocity of this air or gas varies as soon as it enters the chamber.

A special flue D is provided under the chamber C. This flue comprises two compartments of which one serves for the admission of air or gas under pressure in the chamber C, and the other serves to the formation of a regular or steady current, adjustable by means of the cock R.

A chimney E serves for the evacuation of the air and of the dust and is provided on top with any suitable adjusting device F to allow the adjustment of the pressure within the apparatus.

The dust-free material passes through a lower conduit T sealed hydraulically, a cock R, controlling the admission of the liquid required for the purpose.

The lower opening may be adjusted by means of a device O forming an extension of the inner wall of the conduit T.

The multiple element apparatus (Figs. 3 and 4), based on the same principle as the single element apparatus, comprises one or more hoppers A, one or more suitable distributing devices B, a single dust-extraction chamber C, a single chimney E with device for the adjustment of the inner pressure, a single conduit T with adjusting device O at the base, as described above for the single element. Between the chamber C and the conduit T is arranged a special flue D divided into several compartments, of which some are intended for the admission of air or gas under pressure and the others serve

to the formation of steady or regular adjustable currents, as indicated by the arrows.

Fig. 5 gives an instance of one of the numerous arrangements which may be obtained by the juxtaposition of single or multiple elements, the principle of operation remaining the same in all cases.

The distributing or feeding devices B (Fig. 3) in their movement of rotation carry towards the chamber C regular quantities of material in the direction $y-x$. These quantities are at the point y and in the direction of the arrows crossed by currents of air 15 under pressure coming from the compartments D.

Particles which are of a coarser or finer grade or size according to the intensity of the sorting current and the degree of opening 20 of the devices F, leave the apparatus through the chimneys E to be collected by means of suitable devices in hoppers or the like.

The larger sized particles drop into the flues D wherein they come into contact when they reach the lines $m-n$, $m'-n'$, with the liquid in the passages or conduit T.

This liquid is introduced into the conduit T by means of the pipes t , t' , in variable quantities adjusted by means of the cocks R_1 . It rises in the conduit T until it reaches levels $m-n$, $m'-n'$, which depend:

35 1° upon its pressure.

2° upon the pressure of the air or of the gas within the apparatus.

40 3° upon the degree of opening of the lower openings, adjustable by means of devices O, O', which form an extension of the inner walls of the conduits T, T', without break of continuity.

This last feature and the shape of the conduit T produce in the liquid a gyratory motion and at its surface the formation of a meniscus which enable the fine particles of useful material to become wet quite readily (Figs. 6 and 7).

I claim:

50 1. In apparatus for sorting or classifying pulverulent material such as coal dust, the combination of a closed dust extraction chamber having two downwardly converging sloping sides; a vertical flue depending from said chamber, terminating at the base into a narrower discharge conduit; a partition arranged within said flue to form two vertical conduits communicating at their lower end and of which the first has its upper end closed and the second has its upper end opening out into the base of the dust-extraction chamber; a transverse partition in said chamber forming a storage-hopper for the material to be treated having a delivery opening close to the lower

edge of one of the sloping sides of such chamber; mechanically operated means, arranged in said delivery opening, for continuously feeding the material from said storage-hopper onto the lower portion of the last-named sloping side and projecting same across the upper end of the second of the aforesaid vertical conduits; adjustably controllable means for the introduction of gaseous fluid under pressure into the upper portion of the first of said conduits; adjustably controllable means for supplying liquid under pressure to the base of the aforesaid discharge conduit; interchangeable means for adjusting the size of the discharge opening at the lower end of said discharge conduit; an extraction chimney communicating with and leading upwardly from the dust-extraction chamber; and means for adjusting the effective cross-sectional area of the said chimney; all substantially as described.

2. In apparatus for sorting or classifying pulverulent material such as coal-dust, the combination of a closed dust-extraction chamber having two downwardly converging sloping sides; a vertical flue depending from said chamber; baffling means arranged within and extending down a portion of said flue, forming on one side a vertical compartment extending downwardly and on the other side a vertical passage extending upwardly and opening out into the base of the dust-extraction chamber; a transverse partition in said chamber forming a storage hopper for the material to be treated having a delivery opening close to the lower edge of one of the sloping sides of such chamber; mechanically operated means, arranged in said delivery opening, for continuously feeding the material from said storage-hopper onto the lower portion of the last-named sloping side and projecting same across the upper end of the aforesaid vertical passage; adjustably controllable means for supplying gaseous fluid under pressure into the upper portion of the aforesaid vertical compartment of the flue; a vertical discharge conduit extending downwardly from the base of said flue; adjustably controllable means for supplying liquid under pressure to the base of said discharge conduit; interchangeable means for adjusting the size of the discharge opening at the lower end of the said discharge conduit; an extraction chimney communicating with and leading upwardly from the dust-extraction chamber; and means for adjusting the effective cross-sectional area of the said chimney; all substantially as described.

3. In apparatus for sorting or classifying pulverulent material such as coal-dust, the combination of a closed dust-extraction chamber having two downwardly converging sloping sides; a vertical flue depending

- from said chamber; baffling means arranged within and extending down a portion of said flue, dividing the latter into a series of vertical compartments extending downwardly 5 towards the base of such flue and a series of vertical passages, alternating with said compartments, extending upwardly and opening out into the base of the dust-extraction chamber; transverse partitions in said 10 chamber forming a storage-hopper for the material to be treated adjacent each of the sloping sides of such chamber, said hoppers having a delivery opening close to the lower edge of one of the sloping sides of such 15 chamber; a mechanically operated feeding device arranged in the said delivery opening and adapted to feed material from said storage-hopper onto the lower portion of the last-named sloping side and to project same 20 across the upper end of the aforesaid vertical passage; a supply pipe for gaseous fluid under pressure delivering into the upper portion of the aforesaid vertical compartment of the flue; means on the said 25 pipe for adjusting the supply of gaseous fluid therethrough; a vertical discharge conduit extending downwardly from the base of the aforesaid flue; a supply pipe for liquid under pressure delivering into the 30 base of the said discharge conduit; means in the last-named pipe for adjusting the supply of liquid therethrough; means for altering the size of the discharge opening at the lower end of the aforesaid discharge 35 conduit, said means consisting of a series of interchangeable conical nozzles having their largest base of a diameter equal to that of the said lower end of the discharge conduit and their narrowest base of decreasing diameters; an extraction-chimney communicating with and extending upwardly from the dust-extraction chamber; and means for adjusting the effective cross-sectional area of the said chimney; substantially as described. 40 45 4. In apparatus for sorting or classifying pulverulent material such as coal-dust.
- the combination of a closed dust-extraction chamber having two downwardly converging sloping sides; a vertical flue depending from-said chamber; baffling means, arranged 50 within and extending down a portion of said flue, dividing the latter into a series of vertical compartments extending downwardly towards the base of such flue and a series of vertical passages, alternating with said compartments, extending upwardly and opening 55 out into the base of the dust extraction chamber; transverse partitions in said chamber forming a storage-hopper for the material to be treated adjacent each of the 60 sloping sides of such chamber, said hoppers having a delivery opening close to the lower edge of said sides; mechanically operated means, arranged in each of said delivery openings, for continuously feeding 65 the material from said storage-hoppers onto the lower portion of the aforesaid converging sloping sides and projecting same across the upper end of the aforesaid vertical passages; adjustably controllable means for 70 supplying gaseous fluid under pressure into the upper portion of each of the aforesaid vertical compartments of the flue; a vertical discharge conduit extending downwardly from the base of said flue; adjustably controllable means for supplying liquid under 75 pressure to the base of said discharge conduit; interchangeable means for adjusting the size of the discharge opening at the lower end of the said discharge conduit; an extraction chimney communicating with and leading upwardly from the dust-extraction chamber; and means for adjusting the effective cross-sectional area of the said chimney; substantially as described. 80 85

In testimony thereof I signed hereunto my name in the presence of two subscribing witnesses.
